UNITED STATES PATENT OFFICE.

MENDEL COHEN, OF BALTIMORE, MARYLAND.

DISPLAY TRAY FOR JARS.

Application filed March 13, 1928. Serial No. 261,286.

This invention relates to display devices and has special reference to a display tray for jars and the like.

In the handling of many classes of goods such as candies, chewing gum, packages of cough drops and other articles which are vended in small packages it is quite customary to keep such articles or packages in glass display jars. Sometimes such jars have a loosely fitting top while at other times the top is screwed on. In either case in order to sell articles contained in the jar it is necessary to remove the top which tends to a loss of time and to risk of breaking the top or jar.

It will be noted that this is especially desirable in such cases as those in which it is advisable to keep the bulk of the goods free from moist air. For instance, salted peanuts may be kept with the bulk of the goods in the jar to remain fresh, just a few packages being kept on the tray.

One important object of the present invention is to provide, in combination with such a jar, a display tray supported in a novel manner from the jar and projecting laterally therefrom so that a certain proportion of the articles contained in the jar may be held on the tray both for additional display purpose and for ease in handling when sold.

A second important object of the invention is to provide a device of the above character wherein the tray is movable or detachable from the jar when desired.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation showing one form of the invention.

Figure 2 is a top plan view thereof.

Figure 3 is a bottom view of the display tray.

Figure 4 is a plan view of a second form of the invention.

Figure 5 is a view, partly in section, showing the first form of support and the means used for adjustably arranging the same.

Figure 6 is a view of such support removed from the jar and in its collapsed position.

Figure 7 is a bottom view of a second form of tray.

Figure 8 is a view of a second form of support removed from the jar.

Figure 9 is a side elevation of an arrangement wherein the tray is hinged to the jar cap or cover.

Figure 10 is a section through the upper part of such a jar showing the tray in closed or folded over position.

Figure 11 is a section through the top of a jar and a display tray and showing a still further arrangement for supporting the tray.

Figure 12 is a perspective view of the tray support shown in Figure 11.

In that embodiment of the invention wherein the device is applied to the neck of a jar there has been shown in the accompanying drawings an ordinary display jar 10 having a neck portion provided with an annular groove 11 and in the form shown in Figure 1 and Figures 5 and 6 the support for the display tray consists of an arcuate member forming nearly a complete circle. Referring to Figure 5 it will be seen that this member consists of a short tubular section 12 and two arcuate rods 13 which have adjacent ends inserted telescopically in the tubular member 12, the latter being of slightly different curvature to the normal curvature of the rods 13 so that when moved in or out of the tubular member the rods 13 will be frictionally engaged in said member and thus grip and hold in adjusted position. The remaining ends of the rods 13 are turned outward to form parallel prongs 14 and over the greater part of these rods and the member 12 is fitted a tubular rubber cover 15 forming a cushioning means. In some instances, as shown in Figure 6, the tubular section 12 is omitted and when removed from the jar the ends of the rod 13 cross each other, the rod being elastic and contracting to the form shown. In such instances it will be observed that a certain curvature is given the rod 13 so that when the ends 14 are uncrossed and spread apart in fitting on the jar the ends 14 will lie in the same horizontal plane.

In a further form of the device such as is shown in Figures 4 and 8 two rods and covers are used but these rods and covers extend around the jar for less than a semi-circle and the opposite ends of the rods are extended to form two pairs of parallel prongs 16, the covered portions of the rods being indicated at 105

17. In each of these forms rectangular trays 18 are supported on the prongs 16 either by insertion in open sided loop members 19 as shown in Figure 3 or through loops 20 of 5 the type shown in Figure 7. In any of these cases the support is simply placed on the jar in the groove 11 and the loops slipped on the prongs either on one side as shown in Figure 1 or on both sides as shown in Figure 4, the 10 trays acting to hold the prongs from spreading in each case.

In the form in which the device is attached to the cap there is shown a jar 21 having a screw cap 22 and the tray 23 is hinged to the 15 cap at 24, the tray being arranged with a circumferential flange 25 which closes over the cover 22 when in folded position. A suitable stop finger is used in connection with the hinged arrangement to hold the tray substantially horizontal, such a finger being 20 shown at 26.

In the form shown in Figures 11 and 12 the jar 27 has a loose stopper 28 which engages the inner end of a supporting bar 29 25 having its inner end 30 bent to inverted U-shape to fit over the rim of the jar 27. The bar 29 engages a loop 31 formed on the bottom of the tray 32.

In any one of these cases the bulk of the 30 goods is kept in the jar while sufficient for display and immediate sale is placed on the tray.

There has thus been provided a simple and 35 efficient device of the kind described and for the purpose specified.

It is obvious that minor changes may be 40 made in the form and construction of the invention without departing from the material spirit thereof. It is not, therefore, desired to confine the invention to the exact 45 form herein shown and described, but it is desired to include all such as properly come within the scope claimed.

Having thus described the invention, what 50 is claimed as new, is:

1. In combination, a jar having a grooved neck portion, an arcuate band fitting in the 55 groove of the neck and having a lateral horizontal extension, and a display tray supported in horizontal position on top of and detachably connected to said lateral extension.

2. In combination, a jar having a neck provided with a circumferential groove, an 55 arcuate neck embracing device fitting in the groove and provided with a spaced pair of prongs projecting in a horizontal plane from

one side of the device, a display tray supported on said prongs, and means on the underside of the tray to engage said prongs to position the tray thereon.

60

3. In combination, a jar having a neck provided with a circumferential groove, an arcuate neck embracing device fitting in the groove and provided with a spaced pair of prongs projecting from one side of the device, and a display tray supported on said prongs and having loops on its underside receiving said prongs.

65

4. In combination, a jar having a neck provided with a circumferential groove, an arcuate neck embracing device fitting in the groove and provided with a spaced pair of prongs projecting from one side of the device, and a display tray supported on said prongs, said arcuate band having an extension joint therein.

70

5. In combination, a jar having a neck portion provided with a circumferential groove, a pair of similar arcuate members fitting in said groove on opposite sides of the neck and each of less extent than a semi-circle, ends on said members projecting outwardly from the jar to form on each side of the jar a pair of laterally projecting substantially parallel prongs, and a pair of trays each having loops on its underside engageable on the prongs of a respective pair.

75

6. In combination, a jar having a neck provided with a circumferential groove, an arcuate neck embracing device fitting in the groove and provided with a spaced pair of prongs projecting from one side of the device, cushioning means surrounding the portion of the neck embracing device fitting in the groove, and a display tray supported on said prongs, said arcuate band having an extension joint therein.

80

7. In combination, a jar having a neck portion provided with a circumferential groove, a pair of similar arcuate members fitting in said groove on opposite sides of the neck and each of less extent than a semi-circle, cushioning means surrounding said arcuate members, ends on said members projecting outwardly from the jar to form on each side of the jar a pair of laterally projecting substantially parallel prongs, and a pair of trays each having loops on its underside engageable on the prongs of a respective pair.

85

In testimony whereof I affix my signature.
MENDEL COHEN.
